DRILLING APPARATUS

Horace W. Hall, Newton, Mass.

Application December 22, 1931
Serial No. 582,568

17 Claims. (Cl. 144—96)

This invention relates to apparatus for drilling holes, and particularly for drilling holes at an angle through the curved bow portion of rackets for playing tennis, squash and other games.

5 In stringing tennis rackets it is of great importance to have all of the holes on the inside of the bow in center alinement around the bow head so that all the strings will lie in an approximately even plane, and yet the same holes and 10 the stringing on the outside surface of the racket bow must not be in center alinement; for this would result in a splitting of the wood. This necessitates drilling the string holes at an angle through the racket bow, starting at the center 15 on the inside surface and coming out off center at the outside surface. Heretofore, it has required skilled labor to do this drilling even approximately accurate because the bow portion of the racket to be drilled is curved. It is also absolutely necessary 20 to have the holes on the outside of the racket bow in the top portion exactly in predetermined positions with relation to each other because channels must be cut in the wood between said holes in order to sink the strings below the outside surface, and efficient channel routing requires the use of an outside jig form having channel slots that will extend from one hole to another in the racket if the drilling is accurate. 25 Inasmuch as it has been found practically impossible 30 to consistently do this angular drilling through the racket bow sufficiently accurate by hand, the channel routing has heretofore required skillful hand work inasmuch as the outside jig form could not be used because the slots did not line up with the string holes.

Accordingly, one of my objects has been to provide mechanical means to position the racket with respect to the drill, so that the holes both 35 on the inside and outside of the racket will be 40 in predetermined positions with relation to each other, the human element playing but a minor and simple part in this drilling operation.

Another object has been to make said mechanical means so simple and rapid in operation that 45 an unskilled workman can operate the device and drill the holes accurately and speedily.

The foregoing and other objects which will appear as the nature of the invention is better understood, may be accomplished by a construction, 50 combination and operative arrangement of parts such as is disclosed by the drawings. The nature of the invention is such as to render it susceptible to various changes and modifications, and, therefore, I am not to be limited to the construction 55 disclosed by the drawings; but am entitled

to all such changes therefrom as fall within the scope of my claims.

In the drawings:

Figure 1 is a plan view of my drilling apparatus showing tennis racket ready to be moved into engagement with the drill.

Figure 2 is a cross-section on the line 2—2 of Figure 1.

Figure 3 is a front elevation of my drilling apparatus.

Figure 4 is a fragmentary view of a portion of the outer surface of the racket bow showing the cross direction of the stringing.

Figure 5 is a cross-section taken on the line 5—5 of Figure 4 showing the angle of the holes 70 drilled through the racket bow, and in addition showing a portion of the inner surface of the racket bow with holes drilled therethrough.

As illustrated a work bench 12, shown broken away, rests on a floor not shown, and has a pair 75 of runways 13 made of channel iron fastened to it by counter sunk screws 14. Slidable in said runways 13 is a carriage 16 preferably made of metal as shown, which supports the article to be drilled and which has ball bearing wheels 17 80 movable in said runways loosely mounted on stub shafts 18 driven into the sides of said carriage 16. The normal position of said carriage is determined by stop mechanism consisting of adjustable brackets 19 bolted as at 20 to said 85 channel iron runways 13 to which a rubber bumper 21 is fastened as at 22, against which bumper said carriage stops on its return movement away from the drill. Said carriage 16 has an adjustable top 24 on which the article to be 90 drilled rests, which slants upwardly from front to rear as shown in Figure 2 of the drawings, said slant determining the angle at which the holes are drilled through the articles, as the drill itself is mounted in a horizontal position.

A pin 26 is driven into said table top 24 this pin being desirable in order to steady the article to be drilled which is kept in contact with said pin during the drilling operation. Ordinarily said carriage is moved towards the drill by pushing the article to be drilled against said pin.

The article to be drilled as shown in the drawings is a tennis racket 30, although many other articles may likewise be drilled with my apparatus. Around the inner surface of the curved bow head of said racket 30 prick points or slight holes 31 are made which indicate the exact places where the drilling should start. In a strung racket these holes 31 must be in center alinement all the way around the wooden bow

head, the distances they are spaced apart determining the size and shape of the open mesh work of the stringing.

Surrounding the portion to be drilled of said racket 30 is a guide jig 32 which fits the outer surface of said racket snugly, preferably with a slight tendency to cling to it. On this guide jig 32 guide marks 33 are made at particular points, preferably on the outer side thereof, as shown 5 in Figure 3 of the drawings. There is a guide mark 34 preferably made on said carriage top 24 at the front thereof in alinement with the longitudinal axis of the drill stem 38 later described. Just before the drill commences to cut 10 into one of the prick points 30 the operator lines up one of the marks 33 on said guide jig 32 with said mark 34 on the carriage and makes certain that the drill point starts in one of said prick points 31, thereby insuring that the drill 15 will come out on the outside surface of said racket 30 at a predetermined point. As will be noted at the start of the drilling operation the drill stem 38, jig guide mark 33, carriage mark 34 are in alinement with each other and with a 20 prick point 31. Thus it is certain that each outside hole in said racket 30 will be in a predetermined position with relation to the other holes, the marks 33 on said guide jig being the ones which determine where each outside hole 25 shall be located longitudinally around the racket 30. bow.

I have shown a center guide line 35 on said guide jig 32 and as the rackets are marked by a line or groove, not shown, indicating the top 35 center point of the bow, the operator can readily tell if the shape of the racket is correct by noticing if said two center lines are in alinement. The guide jig 32 must be of the correct shape, of course, and if the racket also is, said two center 40 lines automatically line themselves up.

Said guide jig 32 is purposely made lower than said racket 30 so that the operator can directly grasp the projecting upper portion of said racket which enables her to hold it firmly on said carriage top 24, during the drilling operation.

Said carriage 16 is provided with an opening 36 through said top 24 sufficient to accommodate a stationary high speed drill 37, which has a drill stem 38 extending horizontally and preferably 50 tapering to a sharp point to help the operator overcome any tendency of the drill to drift, thereby enabling him to start drilling each time exactly in a prick point 30. A speed of 3,000 revolutions per minute has been found suitable in this 55 work.

Said drill 37 is supported by a common type of bearings 40 fastened to said work bench 12 by screws 41. A drill shaft 42 revolves in said bearings 40 and extends therethrough rearwardly into bearings 43 held to said bench 12 by screws 44. Said drill shaft 42 has a pulley 45 fixed to it on which is a belt 46, driven by some usual source of power not shown.

In order to insure the prompt and automatic return of said carriage 16 to its normal position against said bumper 21 a spring 48 is fastened at one end to said work bench 12 and at the other end to said carriage 16 by screw eyes 49. Said spring 48 is put under tension when said 65 carriage is pushed rearwardly or towards said drill 37 so that when the operator releases her hold on said racket 30 said carriage 16 automatically returns to normal position.

At the rear of each of said channel iron runways 13 is a stop bracket 51 against which said

carriage 16 contacts when it has reached a predetermined limit in a rearward direction which limit is determined by the distance towards said drill said carriage 16 must be pushed in order to have said drill stem 38 drill a hole of even diameter all of the way through said racket bow 30. 80

In Figure 4 of the drawings I have shown an outside portion of the racket bow showing the position thereon of the string holes 54 with relation to each other and the position of the outside stringing 55 which extends diagonally part way across said bow. Should said holes 54 and stringing 55 be in a straight line a splitting of the wool would result, consequently it is necessary to have these outside holes at an angle to each other. An illustration of the usual angle at which said holes 54 are drilled through the racket bow is given in Figure 5 of the drawings. 90

It will be noted in Figure 3 of the drawings that the guide marks 33 on said guide jig 32 extend from both edges only part way to the opposite edge. The reason for this is that each hole on the outside of the racket 30 is off center and on the opposite side of the next hole, consequently the racket must be turned over after 100 half the holes are drilled in order to have them in alternate off center location. During the drilling operation the guide marks 33 which, with the racket in this position, extend to the bottom of said guide jig 32, are the ones which are lined up with the carriage guide mark 34, this arrangement being easier for the eye. After these holes are drilled the racket is turned over, which places the guide marks 33 on the opposite edge at the bottom. To drill the holes at the thicker throat 110 portion of the racket a longer drill stem is used, and as the angle of the holes must be slighter the angle of said carriage top 24 is correspondingly changed.

In order to make my drilling apparatus conveniently accommodate itself to various sizes of rackets and other articles and to enable the operator to drill holes at various points and at different angles, I have illustrated mechanism readily operable by means of which the angle at which 115 the carriage top 24 slants may be changed and said top raised or lowered vertically, as follows.

Said carriage 16 has a base 60 supported by a rib 61, and a ledge 62 integral with said base 60 extends across and projects beyond the front 63 125 of said carriage 16. A shaft 64 is rotatably anchored in said ledge 62, a portion of which shaft is threaded as at 65, and a handle 66 is fixed to the top of said shaft, the turning of which raises or lowers said carriage top 24 vertically. A 130 bearing 67 integral with said front 63 supports the upper part of said shaft 64.

A movable block 70 extends across said front 63 and it has internal threads 71 which engage said shaft threaded portion 65 and make possible 135 vertical movement of said carriage top 24 on said shaft 64. Integral with said top 24 is a large ear 72 at one side and a smaller ear 73 at the other side, both of which ears are supported by a horizontal shaft 74 which is pivotally mounted in said ears 72 and 73. Said shaft 74 also passes through said block 70 thereby connecting said block to said ears. Said block 70 has an integral bracket portion 75 in which there is a curved slot 76 through which a stub shaft 77 140 passes and extends into said ear 72 being threaded at one end into a hand wheel 78. The tightening of said hand wheel 78 on said stub shaft 77 draws the wider outside end of said shaft against said bracket portion thereby holding it 145 150

tightly in whatever position in said slot 76 is desired. To change the slant or angle of said carriage top 24 said hand wheel 78 is merely unscrewed slightly and said top 24 is moved up or down to the desired slant and then said wheel 78 is screwed up again to hold said top in that position.

5 A vertical shaft 80 assists in supporting said block 70 in which it is slidably mounted, being fixed at the bottom to said ledge 62 by a pin 81 and being supported at its upper end by a bearing 82 integral with said front 63.

10 What I claim is:

1. Drilling apparatus comprising a drill, means 15 to support the article to be drilled and adapted to be moved rearwardly and having a guide mark thereon, and a guide jig adapted to surround an outer side portion of the article to be drilled, said jig guide having guide marks thereon, so positioned as to be brought into alinement with said 20 drill cutting portion and said carriage guide mark.

2. Drilling apparatus in combination with the article to be drilled, comprising a drill, means to support said article and adapted to be moved 25 towards said drill, a guide jig of less height than and adapted to surround a portion of the outer side of the article to be drilled, said jig and means having guide marks thereon, adapted to be brought into alinement with the cutting portion 30 of said drill.

3. Drilling apparatus in combination with the article to be drilled, comprising a drill, means to support said article and adapted to be moved to bring said article into contact with said drill and said 35 having a guide mark thereon, said drill and said means being so positioned with relation to each other as to form an acute angle, a guide jig fitted around the outside of a portion to be drilled of said article, said jig having guide marks thereon 40 adapted to be brought into alinement with the cutting portion of said drill and said carriage guide mark.

4. Drilling apparatus in combination with the article to be drilled, comprising a drill, a carriage 45 to support said article and adapted to be moved horizontally and having a guide mark thereon in alinement with the cutting portion of said drill, said article to be drilled having holes in its inner side therein to indicate the starting points for the drilling operation, a guide jig fitting around a portion of the article to be drilled and having 50 guide marks thereon, said drill cutting portion, a said hole, a said carriage guide mark and a said jig guide mark being so positioned with relation to each other that all can be brought into a single horizontal alinement.

5. Drilling apparatus in combination with a racket to be drilled, comprising a drill in horizontal position, a bench, a carriage on said bench 60 adapted to support said racket and adapted to be moved towards said drill, the top of said carriage slanting upwardly from the front rearwardly, said carriage having a guide mark thereon, said article to be drilled having holes therein 65 to indicate the starting points for the drilling operation, a guide jig fitting around the portion to be drilled of said racket having guide marks thereon, said racket projecting above said guide jig, and a pin in and projecting above said carriage 70 against which said racket is adapted to contact during the drilling operation, said drill, cutting portion, a said hole, said carriage guide mark and a said jig guide mark being so positioned with relation to each other that all can 75 be brought into a single alinement.

6. Drilling apparatus comprising a main supporting member, a carriage resting upon and slidable with relation to said member, having a guide mark thereon, a steadyng pin in the front portion of and projecting above said carriage, a drill, a guide jig adapted to rest upon said carriage and having guide marks thereon, said carriage and jig guide marks being so positioned that they can be brought into alinement with each other and with said drill cutting portion.

10 7. Drilling apparatus comprising a main supporting member having runways thereon, a carriage adapted to slide in said runways, the upper portion of said carriage slanting upwardly from front to rear and having a guide mark thereon, a drill mounted in a horizontal position, a guide jig adapted to surround a portion of the article to be drilled and having guide marks thereon, said carriage and jig guide marks being so positioned that they can be brought into alinement 15 with each other and with the cutting portion of said drill.

8. Drilling apparatus comprising a drill in a horizontal position, a movable carriage having a guide mark thereon in alinement with said 20 drill cutting portion, the top surface of said carriage slanting upwardly from front to rear and a guide jig adapted to fit around a portion of the article to be drilled, said guide jig having guide marks thereon adapted to be brought into alinement 25 with said carriage guide mark.

9. Drilling apparatus comprising a drill, a carriage adapted to be moved towards said drill having a guide mark thereon in alinement with said drill cutting portion, said drill cutting portion and the top of said carriage extending in such a direction with relation to each other that their planes form an acute angle, and a guide jig adapted to fit around a portion of the article to be drilled, said guide jig having guide marks 110 thereon adapted to be brought into alinement 115 with the said carriage guide mark.

10. Drilling apparatus comprising a drill in a horizontal position, a carriage adapted to be moved towards said drill and having a guide 120 mark thereon in front of and in alinement with said drill cutting portion and having a steadyng pin therein projecting above said carriage in alinement with said guide mark, the top surface of said carriage slanting upwardly from the front 125 rearwardly, and a guide jig adapted to fit around a portion of the article to be drilled, said jig having guide marks thereon adapted to be brought into alinement with said carriage guide marks.

11. Drilling apparatus comprising a drill in a horizontal position, a movable carriage having a guide mark thereon in alinement with said drill cutting portion, the top portion of said carriage slanting upwardly from the front rearwardly, said 130 carriage having an opening in the top thereof into which opening said drill extends, and a guide jig adapted to fit around a portion of the article to be drilled, said jig having guide marks thereon so positioned as to be brought into alinement with 135 said guide mark and said cutting portion.

12. Drilling apparatus comprising a drill in a horizontal position, a carriage adapted to be moved having a guide mark thereon in alinement with said drill cutting portion, the top surface of 140 said carriage slanting upwardly from the front to the rear, said carriage having an opening in the top thereof into which opening said drill extends, a steadyng pin projecting above the top of said carriage forward of said drill, and a guide jig 150

adapted to fit around a portion of the article to be drilled, said jig having guide marks thereon adapted to be brought into alignment with said carriage guide mark.

- 5 13. Drilling apparatus comprising a main supporting member having runways thereon, a carriage having members attached thereto which are adapted to be moved forwardly in said runways, the top portion of said carriage slanting upwardly 10 from front to rear and having a guide mark thereon, a drill mounted in a horizontal position the cutting portion of which is in alignment with said carriage guide mark and a guide jig adapted to surround a portion of the article to be drilled 15 and having guide marks thereon adapted to be brought into alignment with said carriage guide mark.

14. Drilling apparatus in combination with the article to be drilled, comprising a drill in a horizontal position, a carriage adapted to support 20 said article and adapted to be moved towards said drill, said carriage having an opening therein into which said drill extends and having a guide mark thereon in alignment with said drill cutting portion, a guide jig fitted around the outside of 25 the portion to be drilled of said article and having guide marks thereon, the top surface of said carriage slanting upwardly from front to rear at such an angle that said article contacts with 30 the cutting portion of said drill when moved towards it, said jig guide marks being adapted to be brought in alignment with said carriage guide mark.

15. Drilling apparatus comprising a drill in a horizontal position, a carriage adapted to be moved towards said drill having a guide mark 35

thereon in alignment with said drill cutting portion, the top surface of said carriage slanting upwardly from the front towards said drill, and a guide jig adapted to fit around a portion of the article to be drilled, said jig having guide marks 80 on its outer side.

16. Drilling apparatus comprising a drill mounted in a fixed horizontal position, a supporting member, a carriage adapted to be moved rearwardly on said member the front portion of which is forward of said drill, said carriage having a guide mark thereon in front of and in alignment with the cutting portion of said drill and having an opening in the top therein into which said drill extends, a steady pin fastened in said carriage and projecting above it in a position forward of said drill when said carriage is in normal position, and a guide jig adapted to fit around the outside of a portion of the article to be drilled and having guide marks thereon which marks are 90 so positioned as to be lined up with said carriage guide mark and said drill cutting portion, said carriage top slanting upwardly from front to rear at such an angle that the portion of said article to be drilled will come in contact with 100 said drill cutting portion during the rearward movement of said carriage.

17. Drilling apparatus comprising a drill, a carriage adapted to be moved towards said drill having a guide mark thereon in alignment with 105 said drill cutting portion, and a guide jig adapted to fit around the outer side of a portion of the article to be drilled, said jig having guide marks on its outer side adapted to be aligned with 110 said carriage guide mark.
